S. B. MERRILL

GONG

Filed Oct. 26, 1922

INVENTOR:

Sidney B. Merrill

UNITED STATES PATENT OFFICE.

SIDNEY B. MERRILL, OF CINCINNATI, OHIO, ASSIGNOR TO THE E. W. VANDUZEN COMPANY, OF CINCINNATI, OHIO, A CORPORATION OF OHIO.

GONG.

Application filed October 23, 1922. Serial No. 597,079.

To all whom it may concern:

Be it known that I, SIDNEY B. MERRILL, a citizen of the United States, and a resident of Cincinnati, in the county of Hamilton and State of Ohio, have invented certain new and useful Improvements in Gongs, of which the following is a full, clear, and exact description, reference being had to the accompanying drawings, forming part 10 of this specification.

My invention relates to gongs such as are used in schools and factories for signaling purposes.

Fire gongs, class or period gongs, and 15 gongs to signal change of working shift in factories and shops, have been developed in the past and, particularly in connection with fire gongs, must be carefully constructed so as to be easy and positive of operation.

Among other things, many gongs are so arranged that they are operated on several floors of a building and several places on each floor. A gong hard to operate may 25 become impossible for a child or weakened person to work, and thus ineffective at the time of greatest need.

In the location of gongs in a series on different floors it is a great advantage to have 30 them so confined in lateral dimensions that they can be set on a narrow vertical beam or upright on each floor. One of my objects is to provide a gong in which units can be set one above the other and a mounting space of around three or four inches in 35 width, all that is required for each unit.

One of the objects of my invention is to provide a gong which operates on a laterally pulled handle and which accordingly will 40 not be broken, as by a careless person placing his whole weight on the handle, or a child hanging on it in play.

Another of the objects of my invention is to provide a gong operating device which 45 lies along the center line of the gong itself, thereby cutting down the width of any installation.

Another object is to provide an effective mode of operation of the gong itself from a 50 shaft, said shaft being a rock shaft and thus capable of being connected up with other gongs on the same floor by means of arms on the operating shafts of each bell and a wire or rod connecting the arms.

These various objects and other advan-

tages to be noted I accomplish by that certain construction and arrangement of parts to be hereinafter more specifically pointed out and claimed.

In the drawings,

Figure 1 is a front elevation of the gong operating device with the lines of the gong illustrated.

Figure 2 is a side elevation of the gong.

A casting 1 is provided as a mounting for 65 the device, this casting having three shaft bearings 2, 3 and 4, in which lies a shaft 5. On each end of the shaft 5 located outside of the casting is a standard connecting sleeve 5^a having threaded holes therein, into which the shaft 5 is screwed or pinned and into which connecting shafts 6 are screwed.

Any one of the shafts 6 in a system of 70 bells or gongs arranged according to my invention may have a handle 7 thereon, which is pulled laterally to rock the shaft upon which it is located. This shaft will rock the shafts 5 of each unit in a vertical line. Also any two shafts 6 or 7 may be 75 connected together by means of an arm 8 on each shaft and a wire or rod 9 connecting the arms.

Thus in setting up a set of gongs in a 80 building, some wall is chosen which runs vertically through the building and the gongs are set on each floor in position directly above each other. The shafts or rods 6 are then secured in the sleeves at the top and bottom of each gong and the handle 85 arranged on the shaft most convenient for operation.

For a number of bells on one floor the 90 gong castings are mounted as desired, and an arm and wire connection made as above noted.

The device for operating the gong is designed for ease of operation and positive action.

The clapper or striker 10 is mounted on a pivot stud 11 on the casting, and has a laterally extending arm 12. A spring 13 is connected to the striker bar and tends to pull it towards striking position. A stop 13^a retains the arm in position such that it will lie naturally so as to hold the striker head a fraction of an inch away from the gong A. By tripping the arm 12 and letting the striker be pulled down by its spring until the striker bar contacts with 100 105 110

the stop, enough momentum will be acquired by the head to enable it to tap the gong by reason of looseness of the arm bearing and resilience in the arm.

5 To trip the striker a rocker 14 is provided pivoted in the boss 15 of the casting, this rocker carrying a pawl 16 that contacts with the end of the arm 12. This pawl is held in position in a bifurcated end of the rocker 10 by means of a spring 17, such that it will push up on the end of the arm 12 and then snap past the end of the arm, permitting it to move down freely. On the return of the rocker under influence of its own spring 18, the pawl will snap under the end of the arm 12 again. The boss 15 mounts on its outer end the gong member A.

To operate the rocker it is provided with a depending arm 20 and a dog 21 is mounted 20 on the shaft 5 by means of a collar 22 in such a position that when the shaft 5 is rocked, the dog will contact with the arm 20 and push it over.

The spring that pulls the rocker back to 25 normal position will also return the shaft 5, since the dog does not pass beyond the arm 20.

By extending the operating handle 7 and 30 because of the lever advantage in the rocker and arm device, it does not take much strength to operate the gong and a child can operate a series of them on different floors of a school building without any trouble.

35 The exact method of construction of the sounding apparatus and the exact structure of the connections are not insisted upon by me, and I do not desire the claims that follow to be limited because of my failure to 40 point out alternative structures, which I deem to come within the spirit of said claims.

Having thus described my invention, what I claim as new and desire to secure by Letters Patent is:—

45 1. In a device of the character described, a frame, a gong mounted thereon, a gong striker, a rock shaft mounted on the frame at right angles to the axis of the gong, and a tripping device mounted on the frame and 50 operated by the rock shaft for operating the gong striker.

2. A gong system comprising a series of gongs, frames upon which said gongs are severally mounted, gong strikers for each 55 gong, with tripping devices for each striker, and a continuous rigid linear member mounted to rock on its longitudinal axis, said linear member having devices thereon to operate the strikers for each gong when 60 the linear member is rocked.

3. In a device of the character described, a mounting frame, a gong mounted thereon, a rocker mounted between the gong and the frame, a gong striker adapted to be tripped 65 by the rocker and mounted on the frame, a rock shaft mounted on the frame behind the gong and extending lengthwise of the frame, and means on the shaft to actuate the rocker, whereby the entire device is located within 70 the confines of the gong.

4. In a device of the character described, the combination of a mounting frame, a shaft extending lengthwise of said frame, a gong mounted on the frame, a rocker mounted between the gong and frame so as to rock at right angles to the shaft, a dog on the shaft to actuate the rocker upon a rocking of the shaft, a striker for the gong positioned on the frame between the gong and frame, said rocker adapted to trip the striker 75 to enable it to tap the gong, as and for the purpose described.

SIDNEY B. MERRILL.
